UNITED STATES PATENT OFFICE

GEORGE F. VOIGHT, OF OAKLAND, CALIFORNIA

DESIGN FOR A TOOTHBRUSH HOLDER

Application filed March 11, 1930. Serial No. 34,821. Term of patent 7 years.

To all whom it may concern:

Be it known that I, GEORGE F. VOIGHT, a citizen of the United States, residing at Oakland, in the county of Alameda and State of California, have invented a new, original, and ornamental Design for Toothbrush Holders, of which the following is a specification, reference being had to the accompanying drawings, forming part thereof, and of which—

I claim:

The ornamental design for a toothbrush holder, substantially as shown.

GEORGE F. VOIGHT.
